UNITED STATES PATENT OFFICE

146,777

DESIGN FOR A FIGURINE OR THE LIKE

Grayden W. Phillips, San Jose, Calif.

Application March 23, 1946, Serial No. 127,850

Term of patent 3½ years

(Cl. D29—23)

To all whom it may concern:

Be it known that I, Grayden W. Phillips, a citizen of the United States, residing at San Jose, in the county of Santa Clara and State of California, have invented a new, original, and ornamental Design for a Figurine or the like, of which the following is a specification, reference being had to the accompanying drawing, forming part thereof.

In the drawing:

I claim:

The ornamental design for a figurine or the like, as shown.

GRAYDEN W. PHILLIPS.
